UNITED STATES PATENT OFFICE.

LOUIS LEWIS, OF LONDON, ENGLAND.

STENCIL PRODUCTION.

1,299,969.

Specification of Letters Patent. Patented Apr. 8, 1919.

Application filed June 3, 1915. Serial No. 31,978.

To all whom it may concern:

Be it known that I, LOUIS LEWIS, a subject of His Majesty the King of England, residing at London, England, have invented 5 certain new and useful Improvements in Stencil Productions, of which the following is a specification.

The present invention relates to the mounting and use of wire gauze as a rugose 10 surface in the production of a stencil by methods similar to the tryograph method of Zucatto. On the sheet of wire gauze is laid a sheet of waxed paper, tin foil or like easily puncturable material and the writing 15 or the drawing is executed with a style or blunt point on the puncturable material.

The chief object of the present invention is to hold a wire-fabric stencil producing 20 surface under applied tension during the making of the stencil; this, in a preferred embodiment, such that a power of increasing the tension is realized for the purpose of compensating for or mitigating any expansion or bulging or developing looseness of 25 the fabric which may arise in virtue of the burnishing action of the point or style, or otherwise.

The sheet of wire gauze is for the purpose of the present invention set in a marginal rim, which rim should be moderately 30 rigid or firm in relation to the gauze itself, and in order to produce that even tension of the wire gauze which is so desirable in making a stencil, the framed or marginally 35 rimmed sheet of wire gauze is fitted or placed over and on an elevated surface, then by putting downward pressure on the marginal rim the sheet of wire gauze is positively tensioned both ways or in respect to 40 warp and weft wires, thus securing an avoidance of subversive drag on the stencil sheet with consequent distortion of writing or drawing, also giving a controllable compensation for expansion or bulging due to the 45 burnishing action of the style.

This downward pressure on the marginal rim is by a special mode of carrying out the present invention made so adjustable that increased tension can be applied as required.

50 The invention may conveniently and advantageously be carried into effect as herein-

after described in detail with reference to the accompanying sheets of drawings, in which:—

Figure 1 is a plan view. 55

Fig. 2 an elevation, and

Fig. 3 a sectional elevation on line 3—3 of Fig. 1 of one constructional form of device under the invention.

Fig. 4 illustrates an enlarged sectional view partly broken away on line 4—4 of Fig. 1, but with another form of tensioning means for the fabric applied to the device. 60

Fig. 5 is an enlarged view of the rimmed wire-fabric stencil producing surface, part 65 of the latter being broken away.

Figs. 6 and 7 are enlarged plan view and inverted plan view respectively of parts of the device.

Figs. 8, 9 and 10 are side, plan and side 70 views respectively of part of the tensioning means for wire-fabric.

a designates a dual supporting and light frame or part light frame formed with a ledge *b* on which a removable supporting 75 frame *c* is received with a fairly close fit. If desired the frame *c* may be fixed to the frame *a* or the frames *a* and *c* may be made in one piece. A frame *d* formed with a marginal rim or elevated surface *e* and an intermediate rim or elevated surface *f* rests upon the supporting frame *c* and carries another frame *g* formed with recesses *h*, *i*, the former at the inner edge and the latter intermediate of the inner and outer edges, whereby, when the device is assembled, the rims *f* of the frame *d* will closely fit into the recesses *i* of the frame *g*, and the recesses bound by the rims *e* and *f* of the frame *d* and the recess *h* of the frame *g* will form a 80 substantially fully walled cavity in which a rigid marginal rim *j* of the wire-fabric sheet *k* may be received. The rimmed wire-fabric stencil producing surface *k* rests upon an elevated transparent backing formed by two 85 superposed glass plates *l*, *m*, supported by the frame *a*. The top edges of the side members of the frame *a* and the upper face of the backing *l*, *m* form, as shown, an elevated surface in relation to the bottom of 90 the recesses bounded by the rims *e* and *f*.

The end members of the frame *a* in the

- depicted example are less in height than the side members and the former are ledged at a height corresponding to the height of the side members; thus when the wire-fabric is 5 stretched over the elevated surface the transparent backing will be held against any longitudinal displacement in relation to the wire-fabric by the bending over of the wire-fabric at the ends of the backing.
- 10 Full protection of the original drawing *n* or the like from injury during copying is secured by placing the same between the two plates *l*, *m*.
- 15 Means for applying and maintaining contact pressure between the frame *g* and the frame *d* so as to thereby force down the rim of the wire-fabric and cause the latter to be stretched and held under tension may be variously effected. Simple means for maintaining 20 hand applied pressure consists of a number of clamps *o* secured to the frame *d* or *g* as desired. By furnishing such clamps with movable faces adjustable by screw action, the amount of the applied pressure may be varied from time to time.
- 25 Convenient means for mechanically applying pressure and for thereafter maintaining or varying this pressure is depicted by Figs. 4, 8, 9 and 10. As illustrated the 30 said means is constituted by a pin projection *p* secured to the frame *g* against which a gradually increasing cam or wedge power is brought to force the frame *g* downward. The cam action which is preferred as 35 convenient and compact in ratio to the effective length of the wedge-organ, is constituted of a disk *q* revolubly screwed against a vertical side of the frame *d*, the curved-wedge or cam-face of this disk, which cam-face bears against the casing, being shown 40 by *r* Fig. 9. At *s* is an opening or gap by which one of the projections *p* on the above mentioned frame *g* can readily enter into the disk *q*, provided that the gap *s*, is 45 brought to the top. On turning the disk *q* the pin *p* and the frame *g* are forced down by the operation of the cam-face *r*. In certain cases as where the tracing-device is not required to also function as a duplicator, 50 and other provision is made for holding the stencil material the pins *p* which engage in the disk *q*, may be directly attached to the rigid frame with which the wire gauze is margined.
- 55 By disposing a convenient number of such disks as *q* on the frame *d*, let it be supposed three on the right side and three on the left side and fitting the frame *g* with pins *p* in suitable places an easily controlled 60 tightening of the wire gauze is realized. A tensioning device gives a power of increasing the tension of the wire-fabric *k* for the purpose of compensating for or mitigating any expansion or bulging or devel-

oping looseness of the wire-fabric which 65 may arise by virtue of the burnishing action of the point or style, or otherwise.

It need scarcely be mentioned that the cam faces *r* of the disks *q* for the two sides 70 must be of corresponding action or if looked at individually on the inner face the disks and the cam faces will present contrary aspects.

Having placed the drawing *n* or the like to be copied between the plates *l*, *m* of the 75 elevated backing, the wire-fabric sheet *k* is fitted over the backing and the rim *j* of the said sheet comes to rest in the cavity formed by the elevation *e* of the frame *d* and the recess *h* of the frame *g*, a sheet of 80 stencil material *t* is placed over the wire-fabric *k* and passes and is held between the frames *g* and *d*. With sufficient clearance left between these two frames and between the rim *j* of the wire-fabric *k* and the frame 85 *d*, movement of the two frames toward each other on applying pressure is permitted to thereby tension the wire-fabric *k*. By proper regulation of the pressure, the tensioning of the wire-fabric can be regulated 90 as desired.

In order that easy access may be had to the drawing or to facilitate the reproduction of copies from the produced stencil, it is 95 advantageous to hinge the frame *d* to the frame *c* as illustrated at *u*. In case of reproduction, the wire-fabric *k* is removed and the stencil material *t* with the copy of the drawing or writing is clamped between the frames *g* and *d* so that it will lie substantially flat, while the material to which the drawing is to be transferred will be placed on the plate *l* so as to rest between the latter and the stencil material *t*. The hinging of the frame will in such a case permit a speedy 100 exchange of the material to which the drawing is to be transferred.

Any suitable source of light may be arranged under the transparent backing *e. g.*, a series of electric lamps when artificial 110 light is to be used and in such a case or a comparable case water or other cooling medium may be furnished for preventing undue heating of the transparent backing.

It may be noted here that the size of the 115 mesh of the wire-fabric may vary according to the fineness or coarseness of the printing desired but it must not be so open as to allow the point or style or type to pierce or unduly stress the material of which the stencil 120 is made, by driving or forcing it down into or at the interstices of the fabric. Thus the wire-fabric must be of such a mesh in relation to the impression element, that a succession of more or less fine holes are produced in the paraffin-paper or its equivalent when writing or typing thereon while placed on the wire-fabric. In a form of the 125

invention found to work well a fabric of woven copper wire having 200 strands to the linear inch was used.

What I claim and desire to secure by Letters Patent is:—

- In a stencil producing apparatus, a supporting frame provided with a ledge located below the top of the frame, a second supporting frame mounted on the ledge, 10 two transparent plates supported by said first mentioned frame, a translucent original to be copied, held between said plates, a
- sheet of wire cloth having a rigid marginal rim stretched over the upper transparent plate, a clamping frame consisting of upper and lower clamping members shaped to form a cavity for the rigid marginal rim and clamping means for drawing the upper and lower clamping members together to firmly clamp the rigid marginal rim of the wire fabric therebetween.

Signed at London, England.

In testimony whereof I affix my signature.

LOUIS LEWIS.
